Primary Examiner — Lakiya Rogers*Assistant Examiner* — Altaira Swangin(74) *Attorney, Agent, or Firm* — Larson & Larson, P.A.;
Frank Liebenow(57) **CLAIM**

The ornamental design for a vehicle seat cover with backing, as shown and described.

DESCRIPTION

FIG. 1 is a rear perspective view of a vehicle seat cover with backing showing our new design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a perspective view thereof.

The broken lines depicting non-skid lettering in FIGS. 1 and 2 form no part of the claimed design. The broken lines depicting a vehicle seat in FIG. 8 are environmental subject matter and form no part of the claimed design.
